*The specification in this patent
is not in print.*

W. Whitemore & W. Whitemore, Jr.

Cotton Gin.

Patented Mar. 21, 1833.

William Whittmore & William Whittmore Jr.
Petition Patent

The Schedule referred to in their Letters Patent, and
making part of the same, containing a description in the
words of the said William Whittmore & Wm. Whittmore
for the substance of their improvement in the machine used for
separating the seeds from cotton commonly called the
roller gin. It all to whom the presents shall come.

William Whittmore Esq. & William Whittmore the
younger gentleman both of West Cambridge in the Com-
py of Middlesex in Commonwealth of Massachusetts
send greeting. Be it known that we the said Wil-
liam Whittmore and William Whittmore the younger
have invented made & applied to use a new and use-
ful improvement in the machine used for separat-
ing the seeds from cotton commonly called the roller
gin which invention improvement is specifically de-
scribed as follows namely: The whole machine ^{with} the
improvement is represented in the figure A. in the draw-
ing hereto annexed as a part of this specification. ⁱⁿ
figure A. in the ⁱⁿ drawing is a sectional view of the
said machine, with the improvements & figure
A. represents the clearer hereto after mentioned the
double crank with its pulley connected therewith, figure
A. is the guard herein after mentioned with its thumb
screws. The improvements are colored with red ink.
A. is the bottom part of the frame of the machine which
may be of cast iron or any other substance sufficiently
strong whose construction of iron it may be made
about twenty six inches in half an inch in length and about
one inch in width from outside to outside and there-
by three inches wide on half an inch in width and six inches

March 21, 1833

in width from inside to outside. B. B. are the middle
posts made of iron or other suitable substance, & when of
iron are about eleven inches $\frac{1}{16}$ of an inch in height &
about two inches $\frac{3}{4}$ of an inch wide, and about $\frac{3}{4}$ of an
inch thick, having slots at the upper ends about nine
inches in length $\frac{1}{4}$ of an inch wide. C. C. are posts
of iron or other suitable material & when of iron may be
made about eight inches wide three sixteenths (widest part)
about one half of an inch thick, excepting near the bot-
tom where they are a little thicker, so as to form a shoot
in and be more firm. D. D. are posts of iron or other
suitable material, & when of iron are about eleven inches $\frac{1}{8}$ of an
inch in height & about one eighth of an
inch in width, and about one half of an inch thick at
the top. The posts B & C. may be about eight inches apart
and the posts B. B. may be six and a half inches apart.
E. is a hand wheel of hard wood or it may be of iron or
other suitable material, which wheel is about six inches
of seven eighths of an inch in diameter & about one inch
thick fixed on the shaft by tenons from the journal of
the lower roller f, which shaft passes thro' the centre of
said wheel, at the end of which shaft a crank is fix-
ed to turn the machine. The lower roller f, above referred
to turns in journals in the posts B. B. & may be of cast
iron, steel or other suitable substance, when of iron may
be in length between the posts about seven and one half
inches, & in diameter about fifteen six tenths of an inch & may
be longer when the machine is proportionately larger.

On the shaft at the opposite end of this roller is fixed a
pinion wheel g, about one & a quarter inch in diameter
& about seven eighths of an inch wide having twelve teeth,
a pulley h, about one and a half six tenths of an inch
in diameter, & is a pinion wheel on the shaft of the upper

the roller 5 of the same dimensions with the other pinion
wheel picks which the web plays. The upper metallic
roller of the same length between the posts, of the same
diameter as that before described and is immediately
above it. It is a bare wheel of wood, iron or other suitable
substance, & this wheel is about one quarter in
diameter & about one inch thick & is fixed on the shaft
of the roller 5, in order to turn the same & gives motion
to the under cloth which cloth passes over the roller 5 by
said bare wheel as moved by a hand being over it
by the pulley d, fixed to the shaft of the lower roller.

The roller 5 is made of hard wood & this roller may be
made about an inch & one quarter in diameter & seven
of one quarter inches in length between the posts and is cov-
ered with sand paper to prevent the cloth from slip-
ping upon it & has iron or metallic guards inser-
ted at the ends which turn on seats fixed to the posts C. C.

The roller 6 is of hard wood ^{also} which is deemed best for this
roller & is, & may be about an inch & three eighths
of an inch in diameter, so as to move a little slower than
the roller last mentioned, & is of the same length, & covered
with sand paper like that & has iron or metallic guards
in the ends which turn on seats fixed to the posts B.
B. is moved by the under cloth or felt K stretched tightly
over it. This roller K, with the cloth stretched upon
it comes within about one half of an inch of the under
roller f, with the felt upon it but the centre of the roller
K is higher than the centre of the roller f. K is on a line
with the central point between the rollers f & S & the seats
in which the journals of the roller K turn are so constructed
as to be raised or lowered and fixed so as to raise
or lower the roller K at pleasure in order that it may
come nearer, or be further from the roller f in order to

74960

so that the cotton may be drawn in more readily between the rollers f & g. D. are pieces of sheet copper, one now about two inches and one eighth of an inch on the inside from the posts C. to the studs n. n. and come up about one half of an inch above the cloth or felt, which are held up by the quoins of the rollers i. & l. to prevent the cotton placed on the underlay cloth k. from falling from the side of it. q. are wooden rollers having quoins quoins at the ends turning on the posts D. D. one above the other about five inches & one eighth of an inch apart from the centers of the quoins. These rollers are about one and five sixteenths in diameter & about seven inches three eighths of an inch far long between the posts & are covered with sand paper to prevent the felt from slipping upon them. The centers of the quoins of the roller q. are a little below the centers of the ends of the roller f. (or of the wooden roller) the center of the quoins of the roller q. is about three inches above the center of the ends of the roller f. Over the rollers D. & f. is an underlay piece of felt paper which of gives motion to the roller D. and over the rollers q. & f. is also a like piece of felt 3.53 tightly stitched which gives motion to the roller q. The roller q. with the felt paper over it bears upon the roller f. with the felt paper over it. I. t. are pieces of hard wood, movable upward & downward in the slats in posts B. B. & B. resting upon bays n. n. adjusted to the journals of the upper roller q. and regulated by thumb screws N. N. passing thro' the iron cap N. N. so as to press the rollers f. & q. together and cause them to bear upon each other sufficiently to draw in the cotton placed upon the underlay cloth k. X. X. are pieces of sheet iron; copper or tin on the inside of the posts D. D. and a banding from the posts D. D. to the posts B. B. to the rollers f. & q. held up by the quoins of the roller

March 21, 1833

of which pass thro' them. The pieces of sheet copper were on the outer
stone and extended below the candle's felt 3.5" p.p. which were
to prevent the cotton from falling from the sides of the felt. It is a
guard made of cast steel, about seven & seven eighths inches long
& one & seven eighths of an inch wide & one fourth of an inch thick
bowed tapering down to about one sixteenth of an inch & rounded
polished at the edge, so as not to cut or tear the staple of the cotton.

Which guard is fitted into grooves cut obliquely in the inside of the posts B. B. so that the lower edge may come within about one sixteenth of an inch of the felt, upon the roller and regulated by an adjusting screw 2.2. passing thro' pieces of brass attached by screws to the inside of the posts B. B. (and screwing into the guard. The lower edge of the guard ought to be made to come as near as conveniently may be to the place of bearing of the upper roller g, on the lower roller f, and ought not much to exceed a quarter of an inch in distance from it in order that the staple of the cotton may not be much broken or injured by it. The object of the guard being to prevent the seeds of the cotton from going between the rollers while the cotton is being drawn between the rollers & thereby to separate the seeds from the cotton. The guard should be placed in grooves making an angle of about from fifteen to twenty degrees with the upright posts B. B. b* is a pulley fixed to the double crank c* which receives its motion from a band d passing over it & the wooden wheel e. The double crank c* has journals at each end turning in bearings in the posts D. D. 3 bages fixed thereto which crank is connected to the frame of the clevis c* in such manner as on being turned to move it up and down, the frame of the clevis moves up and down.

March 21, 1833

when the comb is moved up and down by the handle another the serrated edge of the upper comb plate may pass above & below the center of the upper roller or the serrated edge of the lower comb plate, may pass above & below the center of the lower roller q. & that these comb plates may pass so near to their respective rollers as to remove the cotton from the felt as it passes along from between the rollers f. g. i. is a piece of sheet copper iron, or tin fastened by the copper and to the lower corners of the pieces of metal f. g. & may extend obliquely down, so that the lower edge may rest on the end of the frame A. to receive and convey off the cotton after it comes or is removed from the felt. K. is a piece of sheet copper, tin or iron placed above the upper edge of the guard, to prevent the cotton from passing over the top of the guard in case it be stopped up by the workings of the operation. The cotton is placed upon the end of a cloth h. and by its motion, when the machine is in operation is carried up to the lower roller f. g. passes between that and the guard K. & then between the rollers f. g. which assist in drawing the cotton under the guard, whereby the seeds are separated from it, & the cotton being separated from the seeds, then passes from between said rollers, along the end of f. g. B. principally, some small parts of it only, passing on the end of the felt S. from which felt it is removed by the comb plates or cleavers h. & g. & passes off on the sheet copper, tin or iron i. Cloth is used over these rollers B. & f. g. i. in preference to cloth because it is stronger and will retain a better hold on the cotton, & is also more ~~combed~~ ^{taut} and will not stretch so much and can also be put on in one piece & is more durable than cloth. The machine may be turned by the hands, or driven and carried by water steam, or horse power, or any sufficient force. The length of the rollers in the above described machine, are made to overlap nearly with those in common use, in the roller gin, but by the use of the felt above described in the manner before mentioned, cast iron or other metallic rollers may be used with greater convenience.

7490x

March 21, 1833

strayages, which being much finer, stronger, & less liable to sprung than those of wood, may be made much larger than those in common use, & on this account will be preferable. The felt will also better to bear in the cotton than the rollers alone, & to carry it off from between the rollers after it has passed them so that the rollers may not be clogged therewith as happens sometimes in the common roller gin. The chain is designed to remove the cotton from these rollers after it has passed them & be carried from the rollers & to prevent its passing round on the falling & coming again to the rollers to clog them. The office of the guard is as before mentioned to prevent the seed from coming to the rollers when they bear upon each other as in the common roller gin and thereby more effectually to prevent them from clogging them these rollers. It is to be understood that we do not claim the rollers, frame, screws, wheels, copper, iron & iron plate, pulleys or anything heretofore in common use for the purpose of said aid, & that what we hereby claim is all which we claim as new and as one invention & improvement is the guard, rollers, & cleaner above described when used in the manner and for the purpose of said aid. In testimony whereof we have hereunto set our hands this tenth day of March in the year of our Lord eighteen hundred and thirty three.
